UNITED STATES PATENT OFFICE.

GEORGE A. MURRAY, OF CONCORD, NEW HAMPSHIRE.

DESIGN FOR A SEWING CABINET.

Application filed December 27, 1922. Serial No. 4,724. Term of patent 7 years.

To all whom it may concern:

Be it known that I, GEORGE A. MURRAY, a citizen of the United States, residing at Concord, in the county of Merrimack and State of New Hampshire, have invented a new, original, and ornamental Design for a Sewing Cabinet, of which the following is a specification, reference being had to the accompanying drawing, forming part thereof.

Figure 1 is a side elevation of the sewing cabinet, showing my design, and
Figure 2 is a top plan thereof.

I claim:—

The ornamental design for a sewing cabinet as shown.

GEORGE A. MURRAY.
